CLAIM

The ornamental design for a snack box, as shown and described.

DESCRIPTION

FIG. 1 is a front perspective view of a snack box, showing my new design;

FIG. 2 is a rear perspective view thereof;

FIG. 3 is another front perspective view of the snack box shown in FIG. 1 shown in a combined usage state thereof;

FIG. 4 is front elevational view shown in an exploded configuration thereof;

FIG. 5 is a rear elevational view shown in an exploded configuration thereof;

FIG. 6 is a left side elevational view shown in an exploded configuration thereof;

FIG. 7 is a right side elevational view shown in an exploded configuration thereof;

FIG. 8 is the enlarged plan of its top surface thereof;

FIG. 9 is the enlarged plan of its bottom surface thereof;

FIG. 10 is an enlarged detail view of area 10 in FIG. 2 thereof; and,

FIG. 11 is an enlarged detail view of area 11 in FIG. 2. The long dash, short dash broken lines encircling the enlarged views are for annotative purposes only and form no part of the claimed design.
